poration of Michigan

Application March 28, 1941, Serial No. 385,755

29 Claims. (Cl. 172—239)

This invention relates to a follow up system and more particularly to an electrical remote control system in which a power driven member may be made to accurately follow a control member.

The new system may include one or more self-synchronous transmitters actuated by a control member; corresponding self-synchronous receivers for controlling the movement of the power driven member, and a prime mover controlled by the receivers for driving the power driven member. The present system makes it possible for the rotor of the receiver or receivers to be connected directly or through a gear train to the power driven member. Voltages generated in the receivers when there is an angle of disagreement between the receivers and the corresponding transmitters are employed to control the prime mover to bring the power driven member into a position of synchronism, i. e., a position corresponding to that of the control member.

The system of the present invention in certain of its modifications eliminates the usual slip rings of the receivers. In other modifications, where such slip rings are employed, a brush pressure may be made as great as necessary to prevent contact between the brushes and the slip rings being broken when the system is subjected to mechanical shocks. This is of particular importance in controlling large caliber guns as one of the chief difficulties encountered in fire control is the displacement of the brushes from the slip rings of the receivers by the shocks due to firing of the gun. In previous self-synchronous systems in which the torque developed in the receiver was relied upon to bring the receiver into step with the transmitter the brush pressure of necessity was extremely light so that the high speed receivers could accurately follow the transmitters. In the present system the rotors of the receivers are driven from a prime mover of any desired power and rugged slip ring and brush structures can be employed. Also the receivers may be of simple construction and be provided with rugged bearings since the friction in the receiver is overcome by the torque of the prime mover instead of the torque of the receiver.

The system of the present invention is also capable of operation impulsively as the power driven member approaches a position corresponding to that of the control member so that over-shooting due to the inertia of the driven member is prevented and the gun or other mechanism being controlled is brought to its desired position rapidly without hunting. Indicating receivers 55

may also be and preferably are operated from the same transmitters and both the indicating and power control receivers may be of the three wire type in which only three wires are required between a given transmitter and its associated receiver or receivers. No friction dampers are required on the power control receivers since the rotors thereof are positively connected to the power driven member and the present invention 5 also enables indicating receivers without dampers to be employed without danger of spinning. The impulsive operation of the control system at small angles of disagreement between the power driven member and the control member also causes 10 slight vibration of the indicating receivers so that static friction is overcome and the indicating receivers accurately indicate the position of the transmitters and power control receivers. Also, the power control receivers for small angles of 15 disagreement with the transmitters supply a voltage to the system which supplies additional torque to indicating receivers to bring them into 20 agreement with the power control receivers thus increasing the accuracy of the indicating receivers.

An object of the present invention is, therefore, to provide an improved self-synchronous system in which voltages derived from the receivers thereof control a prime mover for bringing 25 a power driven member to zero angle of disagreement with a control member driving the transmitters.

Another object of the invention is to provide a self-synchronous system in which no slip rings 30 and brushes are required on the receivers.

Another object of the invention is to provide a self-synchronous system in which the rotors of the power control receivers are positively connected to a power driven member the position of 35 which is controlled by the receivers.

A further object of the invention is to provide an improved self-synchronous system in which three wires only are required between the transmitters and receivers.

A still further object of the invention is to provide a self-synchronous system in which control of the power driven member is impulsive for small angles of disagreement so as to prevent over shooting of said member or hunting thereof.

A still further object of the invention is to provide an improved relay for a self-synchronous system capable of operating in various ways for controlling actuation of a prime mover by self-synchronous receivers.

Other objects and advantages of the invention

will appear in the following description of the preferred embodiments of the invention shown in the attached drawings in which:

Fig. 1 is a schematic diagram of one embodiment of the system of the present invention;

Fig. 2 is a plan view of a relay suitable for a modified type of self-synchronous system;

Fig. 3 is a vertical section of the relay of Fig. 2 taken on the line 3-3 of Figs. 2 and 4;

Fig. 4 is a horizontal section taken on the line 4-4 of Fig. 3;

Fig. 5 is an enlarged vertical section of a spring contact member employed in the relays of Figs. 2 to 4 inclusive;

Fig. 6 is a fragmentary diagrammatic view illustrating how the relays of Figs. 2 to 5 may be modified for the system of Fig. 1, and also showing the employment of shading coils;

Fig. 7 is a plan view of the core members and armature of the differential relays showing more clearly a preferred shape of the core members and armature and also showing diagrammatically a modified connection of the windings thereon; and

Fig. 8 is a schematic diagram of a portion of a modified system showing another connection of the contacts of the differential relays.

Referring to the drawings, 10 indicates a control member which may be manually or otherwise rotated and 11 indicates a power shaft caused to follow the rotation of the control member 10 by the system of the present invention. This system may include a low speed transmitter 12 having its rotor 13 connected to a shaft 14 provided with a gear 15 meshing with a gear 16 forming part of the control member 10 which may also include a shaft 17 and a crank disc 18. The system may also include a high speed transmitter 19 having its rotor connected to a shaft 21 carrying a gear 22 also meshing with the gear 16 on the shaft 17. Shafts 14 and 21 may also carry indicator dials 23 and 24 respectively.

The stators 25 and 26 of the transmitters 12 and 19 respectively may be connected in parallel to secondary windings 27 and 28 upon a dual excitation transformer 28 provided with a primary winding 30 connected to a suitable source 31 of single phase alternating current power. The stator windings 25 and 26 of the transmitters are preferably closed distributed windings having one secondary winding 27 of the transformer 28 connected across diametrically opposed points in the winding and the other transformer secondary winding 28 also connected across diametrically opposed points of the winding, the connection of the transformer winding 29 to the stator windings 25 and 26 being in quadrature relation to the connection of the transformer winding 27. The transformer windings 27 and 28 have no electrical connection externally of the transmitters 12 and 19 and each secondary transformer winding is preferably placed on an outer leg of a three leg transformer core. The primary winding 30 is preferably placed on the center leg of the core. This construction enables the flux produced by currents in the primary winding to induce voltages in the secondary windings 27 and 28 while at the same time minimizing magnetic interaction between the secondary windings. As disclosed in my Patent No. 2,227,471 granted January 7, 1941, the dual excitation of the transmitters, stabilizes the system and prevents hunting and spinning of any receiver of the indicating receivers thus rendering unnecessary the employment of friction

damping devices therein. The employment of the three leg transformer with separation of the two secondary windings so as to minimize magnetic interaction between the secondary windings 5 still further stabilizes the system over transformers in which both secondary windings are on the second leg of the transformer. While the single closed excited winding shown is preferred because of more efficient use of the winding conductors and less resistance loss, two separate quadrature stator windings each connected to one secondary primary winding can be employed, if desired.

The rotor windings 13 and 20 of the transmitters 12 and 19 are phase wound windings 15 preferably three phase. While I have shown the excited windings as being on the stator and the phase wound windings as being on the rotor, it is apparent that these windings may be interchanged between the stator and rotor but that the construction shown enables a lesser number of slip rings to be employed and also the greatest heat losses ordinarily occur in the excited winding making it preferable to place such windings upon the stator.

The phase wound windings of the slow speed transmitter 12 may be connected by the conductors 32, 33 and 34 to phase wound windings 35 upon one member of a low speed power control 30 receiver 36 and the phase wound windings 20 of the high speed transmitter 19 may be connected by conductors 37, 38 and 39 to a phase wound winding 40 upon one member of a high speed power control receiver 41. The other member 35 of the receiver 36 may be provided with two quadrature windings 42 and 43, the winding 42 having its terminals connected to a winding 44 upon one core 45 of a differential relay 46 and the winding 43 having its terminals connected to a winding 47 upon another core 48 of the differential relay 46. Similarly the other member 40 of the high speed power control receiver 41 may be provided with quadrature windings 49 and 50. The winding 49 may have its terminals connected 45 to a winding 51 upon a core 52 of a differential relay 53 through contacts 54 and 55 of the differential relay 53. The other quadrature winding 50 may have its terminals connected through contacts 56 and 57 to a winding 58 upon another core 59 of the differential relay 53. The contacts 54 and 55 may be shunted by an impedance such as a resistor 60 and the contacts 56 and 57 may be shunted by a similar impedance 61.

The contacts 55 and 57 are carried by an insulating member 62 mechanically connected to the armature 63 of the differential relay 53 so as to be moved upwardly or downwardly in Fig. 1, by movement of the armature 63 toward the core 52 or the core 59 respectively. Contacts 54 and 56 are carried by spring members 64 and 65, which press the contacts 54 and 56 against the contacts 55 and 57 respectively so that the circuits through contacts 54 and 55 and 56 and 57 are closed when the armature 63 is in its central position. The spring members 64 and 65 tend to keep the armature in its central position. Movement of the armature 63 upwardly in Fig. 1 toward core 52 against the spring tension of member 65, breaks the contact 54 and 55 as spring member 64 engages a stop 66 to prevent the contact 54 from following the contact 55. Similarly movement of the armature 63 downwardly in Fig. 1, toward core 59 moves contact 57 away from contact 56 as the spring member 65 en-

gages a stop 67 to prevent contact 56 from following contact 51.

It will be seen that energization of winding 51 of the differential relay 53 to a greater extent than winding 58 of this relay will cause armature 63 to move upwardly in Fig. 1 thus breaking the circuit between contacts 54 and 55 and inserting the impedance 60 into the circuit of winding 51. Similarly when winding 58 of the differential relay is energized to a greater degree than winding 51, the armature will move downwardly breaking the circuit between contacts 56 and 57 and inserting the impedance 61 in the circuit of winding 58. By correctly connecting the windings 51 and 58 and adjusting the spring action of the spring members 64 and 65 the armature can be made to have a continuous oscillatory motion. The result is that if the two windings are energized to the same degree the armature 63 will oscillate about a central position while if winding 51 is energized to a greater extent than winding 58 the armature 63 will oscillate about a position closer to the core 52, and, conversely, if the winding 58 is energized to a greater degree than winding 51 the armature 63 will oscillate about a position closer to the core 59.

If the direction of the single phase field in receiver 41 at a given instant is indicated by the arrow 68, voltages will be induced in the windings 49 and 50 which are in phase and equal in amplitude. If the field indicated by the arrow 68 is rotated by rotating the rotor of the transmitter 19 the voltages induced in windings 49 and 50 of the transmitter 41 will still be in phase but one of these voltages will be greater in amplitude than the other. For example, if the field indicated by the arrow 68 is rotated clockwise the voltage in winding 50 will be increased and the voltage in winding 49 will be decreased. This will energize winding 58 of the differential relay 53 to a greater extent than winding 51. The armature 63 will thereby be biased toward the core 59.

By connecting the differential relay windings 51 and 58 to the receiver windings 49 and 50 respectively so that the flux in the cores 52 and 59 of the differential relay have the same instantaneous direction through the armature 63 of the differential relay as shown by the curved arrows drawn through the armature, movement of the armature toward the core 52 decreases the reluctance of the path of the flux through the core 52 and increases the reluctance of the flux path through the core 59. This increases the total flux through the core 52 and decreases the leakage flux of the winding 51 while at the same time decreasing the total flux through the core 59 and increasing the leakage flux of the winding 58. A portion of this increased leakage flux of the winding 58 adds to the total flux flowing through the armature 63 from the pole faces of the core 52. Both of these effects result in making the armature unstable in its central position and in increasing the pull on the armature toward one of the cores as the armature approaches such core so that the armature tends to move one way or the other from its central position even if the windings 51 and 58 are equally energized. When the armature moves a short distance from its central position in either direction an impedance 60 or 61 is inserted in the circuit on the core toward which the armature moves. Under these conditions the spring member 64 or 65 as the case may be is of sufficient strength to return the armature toward

central position and cause it to pass therethrough, thus setting up the oscillation referred to. The frequency of this oscillation may be varied within wide limits by varying one or more of the following factors: (1) the mass of the armature or the members moved thereby; (2) the restoring spring tension of the spring members 64 and 65; (3) the value of the impedances 60 and 61; (4) the position of the stop members 66 and 67; and (5) the voltage applied to the windings 51 and 58 from the receiver windings 49 and 50. Thus a frequency suitable for a particular installation may be easily obtained.

A second insulating member 70 carrying contacts 71 and 72 may also be actuated by the armature 63 of the differential relay 53. Contacts 71 and 72 engage stationary contacts 73 and 74 respectively upon downward and upward movement respectively of the armature 63. Contacts 71 to 74, inclusive, in conjunction with contacts actuated by the armature 75 of the differential relay 46 may control a third differential relay 76. Armature 75 of differential relay 46 is mechanically connected to an insulating member 77 carrying contacts 78 and 79 which engage contacts 80 and 81 respectively carried by spring members 82 and 83 respectively. Spring member 82 engages a stop 84 upon upward movement of the armature 75 to break the circuit through contacts 79 and 81 upon downward movement of the armature 75. Contacts 78, 80, and contacts 79, 81 are in a series circuit leading from one conductor 88 connected to one source of a single phase alternating current 89 to contacts 71 and 72 of the differential relay 53. Contact 73 of differential relay 53 adapted to be engaged by contact 71 on downward movement of the armature 63, is connected to a conductor 90 leading to a winding 91 upon one core 92 of the differential relay 76, and contact 74 adapted to be engaged by contact 72 upon upward movement of armature 63 of differential relay 53, is connected to a conductor 93 leading to a winding 94 on the other core 95 of differential relay 76. The other terminals of the windings 91 and 94 of the differential relay 76 are connected to a conductor 97 leading to the other side of the source 89.

The armature 75 of differential relay 46 is also mechanically connected to a second insulating member 99 carrying contacts 100 and 101 which are both connected to the conductor 88 leading to one side of the source 89. A stationary contact 102 is positioned to be engaged by contact 100 upon downward movement of the armature 75 of differential relay 46 and it will be noted that contact 102 is connected to the conductor 90 so as to be in parallel with contact 73 of differential relay 53. Similarly, a stationary contact 103 is positioned to be engaged by contact 101 upon upward movement of the armature 75 of the differential relay 46 and contact 103 is connected to conductor 93 so as to be in parallel with contact 74 of relay 53. Any substantial movement of armature 75 of differential relay 46 away from its central position breaks the series circuit from one side of the source through contacts 78 and 80, or 79 and 81, so as to disable contacts 71 to 74 inclusive, of differential relay 53. However either contacts 100 and 102, or contacts 101 and 103, of differential relay 46, complete circuits through the windings 91 and 94

of differential relay 76 upon movement of the armature 75 of differential relay 46.

The windings 44 and 47 of differential relay 46 are preferably connected so that the instantaneous values of flux through the armature 75 thereof are in opposite directions as shown by the curved arrows through the armature 75. Movement of the armature 75 away from its central position, for example, upwardly in Fig. 1 will decrease the reluctance of the flux path through core 45 and at the same time increase the reluctance of the flux path through the core 48. The flux through the core 45 tends to increase and the leakage flux of winding 44 to decrease. The flux through the core 48 tends to decrease but the leakage flux of winding 47 tends to increase. The increase leakage flux from the winding 47 opposes the flux through the armature 75 from the pole faces of core 45 and also the inductance of the winding 44 on core 45 increases due to the lower reluctance in its flux path, thus restraining increase in current through winding 44, so that the flux through armature 75 from the pole faces of core 45 does not increase greatly due to movement of the armature 75 toward the core 45. For a similar reason the flux through armature 75 from the pole faces of core 48 does not decrease greatly due to movement of the armature away from the core 48. Thus the force acting on the armature is not greatly increased by movement of the armature 75 toward one of the cores. By correctly adjusting the spring tension of the spring members 82 and 83 the armature 75 may be made to move upwardly or downwardly substantially proportional to the difference in energization between the windings 44 and 47 of the differential relay 46 so that this relay becomes substantially "deadbeat" instead of impulsive as was the case of the connection of the windings of differential relay 53.

If the direction of the single phase field in the low speed power control receiver 36 is indicated by the arrow 105, voltages are induced in windings 42 and 43 of the receiver 36, which are of the same phase and equal in amplitude. Rotation of the field indicated by the arrow 105 by rotation of the rotor of the transmitter 12 will induce unbalanced voltages in the windings 42 and 43 of the receiver 36 to actuate the differential relay 46. For relatively large angles of disagreement between the rotor of the receiver 36 and the transmitter 12 either contacts 78 and 80 or 79 and 81 are opened so that the differential relay 46 of the low speed receiver 36 takes control of the differential relay 76 through its contacts 100 to 103 inclusive. For small angles of disagreement between the receiver 36 and transmitter 12 the contacts 78 and 80 as well as contacts 79 and 81 of differential relay 46 are closed and contacts 100 and 102 are open as well as contacts 101 and 103; thus control is shifted to the differential relay 53 of the high speed receiver 41 through its contacts 71 to 74 inclusive.

In the preferred embodiment of the present invention the rotor shaft 106 of the low speed receiver 36 carries a gear 107 meshing with a gear 108 on the power driven shaft 11. The differential relay 46 is also carried by a continuation of the shaft 106 of the low speed receiver 36 with the contact carrying insulating members 77 and 88 actuated by a member projecting axially in alignment with the shaft 106. The insulating members 77 and 88 are preferably held against

rotation. In order to provide for rotation of the differential relay 46 with the rotor shaft 106, a connection 109 permitting relative rotation between the insulating members 77 and 88 and the differential relay may be provided. Similarly the rotor shaft 110 of the high speed receiver 41 may be provided with a gear 111 meshing with the gear 108 and the differential relay 53 associated with the receiver 41 may be carried by a continuation of the shaft 110. Preferably the insulating member 62, spring members 64 and 66 and associated contacts and stops are also carried by the rotor shaft 110. The insulating member 70 and its associated contacts are preferably held against rotation and a connection 112 is provided between insulating member 70 and insulating member 62 to enable relative rotation therebetween. Axial movement may however be transmitted through the connections 109 and 112 for moving the insulating members 88 and 78 respectively. The connection 109 is illustrated on a larger scale in Fig. 6 and may comprise a casing 113 attached to the insulating member 77 and having a screw threaded bore 114. An axially extending member 115 may have an enlarged head 116 positioned with the bore 114, being held in place by a screw threaded plug 117 provided with a bore 118 for the member 115. Such a joint provides for relative rotation while transmitting axial movement.

The differential relay 76 may control a prime mover 119 which is shown by way of example as a reversible single phase induction motor of the condenser type. The rotor 120 of the motor 119 may drive the shaft 11 through any suitable speed reducing device such as a gear train, for example, a gear 121 meshing with a gear 122 upon the shaft 110 of the high speed receiver may drive the shaft 11 through the gear 111 and gear 108. The stator winding of the motor 119 may include two quadrature windings 123 and 124 having a common terminal connected to the conductor 87 leading to one side of the source 89. The armature 124' of the differential relay 76 may be mechanically connected to contacts 125 and 126 and be adapted to alternately engage contacts 127 and 128, respectively, so as to cause rotation of the rotor 120 of the motor 119 in one direction or the other. Any suitable spring device (not shown) may be employed to return the armature 124' to its central position. Since only one of the windings 91 and 94 of the differential relay 76 is energized at a given time there is no opposing force due to energization of the other winding so that the relay 76 develops much more power than the differential relays 46 or 53 even if all of these relays are of the same size and construction. Thus a standard relay usable in all three positions illustrated may be employed merely with different connections. The relay 76 may be built of small size and still develop a large amount of power. If the motor 119 can be small in size for a given installation the relay 76 can be dispensed with and the motor windings connected directly to the contacts 100 to 103 of differential relay 46 and 71 to 74 of differential relay 53 in a manner which is apparent from Fig. 1 so as to energize the coils 123 and 124 of the motor 119 directly.

It is apparent that all of the contacts actuated by the differential relay 46 may be carried on the shaft 106 of the low speed receiver 36 in which case it will be further apparent that a plurality of slip rings will be required for connecting these contacts to external circuits.

Also, all of the contacts of the differential relay 53 can be carried by the shaft 110 of the high speed receiver 41 in which case a plurality of slip rings will be required for connection to the various contacts. Alternately the differential relays 46 and 53 may be separate from their respective receivers with slip ring connections between the rotor windings of the receivers and the corresponding differential relays. In such case relays of the type disclosed in Figs. 2 to 4 may be employed to perform the same function as the differential relays 46 and 53 shown in Fig. 1.

Referring to Figs. 2 to 4, inclusive, the differential relay may include a metallic frame 126 having side members 127 and end members 128. The cores 129 may be positioned in slots 130 in the end members 128 and held in adjusted position by set screws 131. The cores 129 are preferably of laminated construction and are provided with operating coils 132. It will be apparent that the opposed cores 129 provide a substantial diamond shaped opening therebetween in which an armature 133 preferably of laminated construction is positioned. The armature 133 is secured to a pivoted member 134 attached at its lower end to a cross shaft 135 journaled at 136 in downwardly projecting members 137 secured to the side frame members 127.

An upwardly projecting portion of the pivoted member 134 has secured thereto a cross member 138 of insulating material. Cross member 138 carries a pair of end contacts 139 adapted to engage adjustable stationary contacts 140 upon movement of the armature 133 from central position. The cross member 138 also carries a pair of intermediate contacts 141 adapted to engage a pair of spring pressed contacts 142. The stationary contacts 140 and the spring pressed contacts 142 are supported in upstanding cross members 144 of insulating material secured to the side frame members 127.

The structure supporting the spring pressed contacts 142 is shown in large scale in Fig. 5. The contact 142 may comprise an elongated member having a shoulder 143 intermediate its ends. The contact making end of the contact member 142 extends through an aperture 145 in one end of a cylindrical adjusting member 146 having its outer surface screw threaded and received in a screw threaded bore 147 in the insulating cross member 144. The adjusting member 146 has an enlarged bore 148 screw threaded for a portion of its length, the bottom of the bore providing an abutment for the shoulder 143 of the contact member 142. A threaded plug 149 is received in the bore 148 in the member 146 and a compression spring 150 is positioned between the plug 149 and the shoulder 143 to resiliently urge the contact 142 to the left in Fig. 5. A locking nut 151 is screw threaded upon the member 146 against the insulating member 144 for holding the device in adjusted position. It will be apparent that rotation of the supporting member 146 will move the contact member 142 toward or away from its cooperating contact 141 carried on the movable cross member 138 and that rotation of the plug 149 will adjust the spring pressure on the contact member 142.

When the armature 133 and insulating cross member 138 secured thereto are in central position both contacts 142 are normally adjusted to the engagement with their cooperating contacts 141. The springs 150 thereby act as centering springs for the armature 133. Upon movement

of the armature 133 and the insulating cross piece 141 away from central position against the action of one of the springs, the other contact member 142 will break contact with its associated contact 141 since the shoulder 143 of the latter mentioned contact member 142 will prevent said contact member 142 from following its cooperating contact 141. It will be appreciated that the spring pressed contact structure shown in Fig. 5 operates similarly to the diagrammatic spring pressed contact structures involving spring members 64, 65, 82 and 83 shown in Fig. 1. The structure of Fig. 5 is, therefore, preferably employed in a circuit such as shown in Fig. 1 instead of the diagrammatic spring pressed contact structure shown therein.

Referring to Fig. 6 it is apparent that instead of supporting the contacts upon the relay structure itself the movement of the armature 133' may be transmitted to contact carrying members. For example any suitable force transmitting mechanism such as a link 155, pivoted to the member 134 at 136 and a lever 157 at 158, may be employed to transmit axial motion to the axial movable member 115 carrying a contact member 71 previously described. Preferably the axially movable member 115 is coaxial with the shaft of the receiver as also previously described. Furthermore, it is preferably in alignment with the center of gravity of the relay structure so that the relay may be carried by the shaft of a receiver without unbalancing the rotating members of the receiver. By connecting the axially movable member directly to the armature, the link 155 may be directly extended and the lever 157 eliminated.

Again referring to Fig. 1 the system therein disclosed may also include a low speed indicating receiver 160 and a high speed indicating receiver 161. These receivers may include a phase wound winding 162 and 163, respectively, the winding 162 of the receiver 160 being connected through conductors 32, 33 and 34 to the phase wound winding 13 of the low speed transmitter 12 and the phase wound winding 163 of the high speed receiver 161 may be connected through conductors 37, 38 and 39 to the phase wound winding 20 of the transmitter 19. The indicating receivers 160 and 161 are preferably of the short circuited secondary type and have short circuited windings 164 and 165 respectively. The short circuited windings are preferably upon the rotor but it is apparent that these windings could be upon the stators with the phase wound windings 162 and 163 upon the rotors. In either case the rotor of the low speed receiver 160 is provided with a shaft 166 carrying an indicating dial 167 and the rotor of the high speed receiver 161 is provided with a shaft 168 provided with an indicating dial 169. The shafts 106 and 110 of the low speed power receiver 36 and high speed power receiver 41, respectively, may also be provided with indicating dials 170 and 171, respectively, if desired.

Since all of the receivers disclosed in Fig. 1 have no excitation directly from a source of alternating current, it is preferred to provide condenser banks 172 and 173 for supplying exciting current for the low speed and high speed receivers, respectively. The condensers of these condenser banks may be of the correct capacity or as many condenser banks as necessary may be employed to maintain the power factor of the system substantially at unity.

Both the types of power control receivers

and 41 and the indicating receivers 160 and 161 of the system of Fig. 1 have two points of synchronism with their transmitters. For this reason it is preferred to gear the slow speed transmitter 12 to its control shaft 17 so that the transmitter rotates at half the speed of the control shaft 17. That is the gear 15 on the shaft of the low speed transmitter 12 should be twice the diameter of the gear 16 of the control shaft 17. Similarly the gear 107 on the shaft 106 of the low speed receiver 36 should be twice the diameter of the gear 108 upon the control power shaft 11. The indicating dials 23, 167 and 170 of low speed transmitter 12, indicating receiver 160, and low speed power control receiver 36, respectively, are therefore graduated so that each half of the dial indicates 360°. These dials will therefore directly indicate the angular position of the shaft 11 from a given reference point directly in degrees.

As indicated above the low speed transmitter 12 and power control receiver 36 control the operation of the prime mover 119 to bring the shaft 11 to a relatively small angle of disagreement with the control shaft 17. When a predetermined small angle of disagreement is reached the high speed system including the transmitter 19 and receiver 41 takes control. Any suitable speed ratio $1/n$ between the high speed system and the low speed system may be employed although it is convenient to make $1/n$ equal to $1/36$ to give a speed ratio of 1 to 36. It is apparent that the slow speed system must bring the shaft 11 into a region within $1/2n \times 360^\circ$ on either side of synchronism with the control shaft before the control can be transferred to the high speed system as otherwise the high speed receiver would tend to control the motor 118 to drive the shaft 11 away from synchronism. With the ratio of 1 to 36, this means that the slow speed system must bring the shaft 11 to within $1/72 \times 360^\circ$ or 5° on either side of synchronism. In order that correct control by the high speed system be assured, it is preferable to adjust the system so that the low speed system brings the angle of disagreement between the shafts 11 and 17 to substantially less than 5°, for example, 3° to 4° before relinquishing control to the high speed system.

The total angle of control of the high speed system for a speed ratio of 1 to 36 is therefore always less than a 10° movement of the power shaft 11 and each high speed transmitter or receiver makes one half revolution for each 10° movement of the power shaft 11. Each half of the high speed dials 24, 169 and 171 can, therefore be graduated from 0 to 10° and these dials will then act as verniers for the low speed dials 23, 167 and 170. Since the receivers develop their maximum torque at 45° angle of disagreement instead of at 180° as with conventional receivers, their torque gradient at zero angle of disagreement is greater than for conventional receivers and larger dials can be employed without decreasing the sensitivity of the systems. Since the self-synchronous machines rotate at half speed of conventional receivers, the indicating dials can be made larger without increasing the inertia load on the system.

The operation of the relays may be modified by placing shading coils 175 (Figs. 6 and 7) in the faces of the armature 133'. Such shading coils may comprise a single turn conductor of low resistance placed in slots in faces of the armature. These shading coils resist either an in-

crease or decrease of flux through the armature, thus producing a more uniform force on the armature minimizing the usual vibration of the armature at double the frequency of the energizing voltage and producing a greater resultant force. The shading coils also slow down the action of the armature thus making the low speed differential relay more nearly "deadbeat" and decreasing the frequency of oscillation of the high speed differential relay. While the shading coils have been shown on the armature only, it is apparent that they can be applied to either the armature or core pole faces or both.

15 The shape of the core and armature also has an important bearing upon the operation of the relays. By providing a substantially diamond shaped armature 133' with the pole faces of the cores 129 parallel to the faces of the armature 128 and at an angle to each other, the range of movement of the armature can be increased without increasing the air gap and at the same time the forces on the armature are balanced laterally of the relay. The angle which the 20 pole faces make with the direction of movement of the armature can vary to a considerable degree but best results are obtained when this angle is approximately 30°. This construction also enables the pole faces of one of the cores 25 129 of the relay to be maintained separate from the pole faces of the other core except for a small area 176 adjacent the extreme ends of the pole faces. The external faces 177 of the ends of the cores may diverge from each other so that 30 the magnetic interaction between the cores and between their associated windings can be controlled by varying the angle of divergence. The smaller the angle between the faces 177 the greater will be the amount of leakage flux which 35 crosses the gap between these faces, thus causing interaction between the flux of the two cores. By varying this angle the interaction between the flux of the two cores can be varied within wide limits so that the effect of change in leakage flux due to armature movement can be 40 made to increase or decrease the force acting on the armature as the armature moves from central position, depending upon the connection of the windings. That is to say, if the windings 45 50 are connected so that the leakage flux from one winding adds to the flux passing from the pole faces of the other core through the armature, the increase of force on the armature as the armature moves from central position can be 55 made to rapidly increase if the angle between the faces 177 is made small. On the other hand connecting the windings so that the leakage from one winding opposes the flux passing from the pole faces of the other core through the armature, making the angle between the faces 177 small, tends to minimize any increase in force 60 on the armature due to movement toward one of the cores. An angle in the neighborhood of 90° between the faces 177 with the areas 176 65 positioned quite close together has been found to produce a relay which operates efficiently for either connection.

It is in order to further control the nature of the action of the differential relays, a portion of 70 the turns on one core can be connected in the same circuit as the windings on the other core as shown in Fig. 7. Thus the main winding 178 on one core 129 may be connected in series with an auxiliary winding 179 having a lesser number 75 of turns on the other core. Similarly the main

winding 180 on the other core may be connected in series with an auxiliary winding 181 on the first mentioned core. By connecting the windings so that the two windings on the same core oppose each other an increase in excitation of one circuit will cause the flux in the core having the main winding to increase while causing the flux in the other core to decrease thereby increasing the resultant force on the armature by a given unbalance of the excitation voltages for the two circuits. The reverse connection of the windings of the circuits so that the windings on one core aid each other will have the reverse effect. It will be apparent that the auxiliary windings 179 and 181 could be employed to constitute the impedances inserted into the main windings 178 and 180 respectively in a manner similar to that by which the impedances 60 and 61 are inserted into the windings 51 and 58 of the high speed differential relay 53 of Fig. 1. By variously connecting the main and auxiliary windings a still further control of the frequency of oscillation of the impulsive relay can be obtained.

In describing the operation of the system of Fig. 1 it will be first assumed that the control shaft 17 and the controlled power shaft 11 are in synchronism. That is to say, that there is no angle of disagreement between the shafts. This means that the quadrature windings on the rotor of both the high speed power control receiver 41 and low speed power control receiver 46 are aligned with the fields in these receivers so that the voltages induced in the quadrature windings in each receiver are equal. Under these conditions the armature 75 of the low speed differential relay 46 is in central position and the contacts 78-80 and 79-81 thereof are closed. Also the contacts 100-102 and 101-103 of this relay are open. The armature 63 of the high speed differential relay 53 is oscillating about a central position, since this armature is in unstable equilibrium and the contacts 54 and 55 and 56 and 57 of this relay are alternately inserting the impedances 60 and 61 into the circuits of the windings 51 and 58, respectively, of this relay. This means that the contacts 71-73 of this relay are being closed alternately with contacts 72-74. When the contacts 71 and 73 are closed a circuit may be traced from the source 89 through conductor 88, contacts 78-80 and 79-81 of differential relay 46 through contacts 71-73 of differential relay 53, conductor 99, winding 91 of differential relay 76, and conductor 97 to the other side of the source 89. Thus, winding 91 of differential relay 76 is closed whenever contacts 71 and 73 are closed. In a similar manner whenever contacts 72 and 74 are closed a circuit may be traced from one side of the source 89 to the conductor 88, contacts 78-80 and 79-81 of differential relay 46, contacts 72 and 74 of differential relay 53, conductor 93 of winding 94 of differential relay 76, and then through conductor 97 to the other side of the source 89. Thus windings 91 and 94 of differential relay 76 are alternately energized to cause the armature 124 of this relay to close contacts 127 and 125 alternately with contacts 126 and 128 of relay 76. Under these conditions differential relay 76 operates impulsively in the same manner as differential relay 53.

When contacts 127 and 125 of differential relay 76 are closed a circuit may be traced from one side of the source 89 through conductor 88, contacts 125 and 127, field winding 123 of the motor 119 and conductor 97 to the other side of the source. When contacts 126 and 128 of differential

relay 76 are closed a circuit may be traced from one side of the source 89 through conductor 88, contacts 126 and 128, field winding 124 of the motor 119, and conductor 97 to the other side of the source. Thus, reverse impulses are impressed upon the motor 119, but since armature 63 of differential relay 53 and the armature of the differential relay 76 are oscillating substantially about their central position no resultant rotation of rotor 120 of motor 119 is produced because of the inertia of the motor and the parts driven thereby. These pulses are merely sufficient to somewhat vibrate the entire system so that static friction any place in the system does not permit any slight angle of disagreement to persist even in the indicating receivers 160 and 161.

If the control shaft 17 is rotated by the control member 18, an angle of disagreement will at least temporarily exist between the shaft 17 and the shaft 11. Rotation of the rotor winding 20 of the high speed transmitter 19 will cause the field indicated by the arrow 68 to rotate in the high speed receiver 41. This will unbalance the voltages induced in the quadrature windings 49 and 50 thereof. The armature 63 of the high speed differential relay 53 will continue to oscillate but will now oscillate about a position spaced from the central or neutral position so that one of the pairs of contacts 71-73, or 72-74 will be closed for a greater length of time than the other. If it be assumed that contacts 72 and 74 are closed for the greater length of time winding 94 of the differential relay 76 will be energized for a greater length of time than winding 91 of this relay so that contacts 125 and 127 are closed on an average for a greater length of time than contacts 126 and 128. A resultant torque will be produced in motor 119 to drive the shaft 11 in the correct direction to eliminate the angle of disagreement between the shafts 11 and 17, at which position, the windings 49 and 50 in the high speed receiver become aligned with the field indicated by the arrow 68 so that these voltages are again equal and the impulses supplied to the windings of the motor 119 are again equal and no resultant rotation is produced.

If the control shaft 17 is rotated with sufficient rapidity to cause the angle of disagreement between the shafts 11 and 17 to be substantially greater than the angle at which the low speed system takes control the voltages induced in the windings 42 and 43 of the low speed power receiver 36 will be sufficiently unbalanced to move the armature 75 of the low speed relay 46 and open one of the pairs of contacts 78 and 80 or 79 and 81. Since these pairs of contacts are in series with the control contacts of relay 53 this will break the control circuit of the high speed differential relay 53 previously traced. Movement of the armature 75 will also close one of the pairs of contacts 100-102 or 101-103. If the contacts 100-102 are closed a circuit may be traced from one side of the source 89, conductor 88, contacts 100-102, conductors 90, winding 91 of differential relay 76 and conductor 97 to the other side of the source 89. If the contacts 101-103 are closed, a circuit may be traced from one side of the source 89 through conductor 88, contacts 101-103, conductor 93, winding 94 of differential relay 76 and conductor 97 to the other side of the source. Thus one or the other of the windings 91 or 94 of differential relay 76 will be energized to close one of the pairs of contacts 125-127, or 126-128, to cause the motor 119 to drive the shaft 11 in the correct

direction to reduce the angle of disagreement between this shaft and shaft 17. Under these conditions the energization of the motor is constant and full power is applied thereto. When the angle of disagreement is reduced to the predetermined angle at which the high speed system takes control, the armature 75 of low speed differential relay 46 will move back under control of a spring contact 82 or 83 so that both pairs of contacts 78-80 and 81-83 are closed and both pairs of contacts 100-102, and 101-103 are open. This restores control to the high speed differential relay 53 so that the shafts 11 and 17 are brought to final synchronism in the manner previously described.

In Fig. 8 is shown a modified connection of the contacts of the differential relays. In this figure the same reference numerals used in Fig. 1 are employed for elements identical with those of Fig. 1 and the reference characters of Fig. 1 with primes are employed for elements having functions similar to those of corresponding elements of Fig. 1. Thus contact 54' of Fig. 8 is a spring pressed contact of the type shown in Fig. 5 and operates in a manner equivalent to the spring pressed contact 54 of Fig. 1. Contact 56' cooperates with contact 55' and is carried by an insulating member 62' actuated by the armature of a high speed differential relay such as the relay 53 of Fig. 1. Contact 56' is also carried by the insulating member 62' and cooperates with a spring pressed contact 57'. The pair of contacts 54' and 55' inserts the impedance 60 into the circuit of winding 51 of the high speed differential relay 53 of Fig. 1 and the pair of contacts 56' and 57' insert the impedance 61 into the circuit of winding 58 of the differential relay 53 of Fig. 1, when the corresponding pairs of contacts are opened. Contacts 71' and 72' are carried by the same insulating member 62' rather than a separate insulating member and cooperate with contacts 73' and 74', respectively, to close control circuits for the winding of differential relay 76 of Fig. 1 through conductors 90 and 93, respectively.

An insulating member 77' is operated by a low speed differential relay such as the relay 46 of Fig. 1 and carries contacts 78' and 79' cooperating with spring pressed contacts 80' and 81', respectively. The contacts 78'-80' are in series with contacts 71'-73' of the high speed differential relay so that the former contacts control the operation of the latter contacts. Contacts 78' and 81' of the low speed differential relay are in series with contacts 72' and 74' so as to similarly control the operation of the latter contacts. Spring pressed contacts 80' and 81' are connected to conductor 88 leading to one side of the source 89. The insulating member 77' for the low speed differential relay also carries contacts 100' and 101' which cooperate with contacts 102' and 103', respectively. Contacts 100' and 101' are connected to one side of the source 89 by the conductor 88 and contacts 102' and 103' are connected to conductors 90 and 93 respectively in parallel with contacts 73' and 74', respectively, of the high speed differential relay.

The connection of Fig. 8 produces a result substantially the same as the connection shown in Fig. 1, but there are never more than two pairs of contacts in series, whereas in Fig. 1 the pair of contacts 78-80, the pair of contacts 79-81, and either of the pairs of contacts 71-73 or 72-74 may be in series. The structure of Fig. 8 thereby reduces contact resistance and the likelihood of

improper operation. When the angle of disagreement between the low speed transmitter 12 and its power control receiver 36 of Fig. 1 is sufficient to operate the low speed differential relay 46, for example, to move the insulating member 77' of Fig. 8 downwardly in Fig. 8, contacts 100' and 102' carried thereby are closed to complete a circuit from the source 89 through conductor 88, contacts 100' and 102' to conductor 90, one winding 91 of the differential relay 76 of Fig. 1 and conductor 97 to the other side of the source 89. Under these conditions movement of the insulating member 62' by the high speed differential relay can have no effect upon the operation of differential relay 76 of Fig. 1, as downward movement of this insulating member in Fig. 8 merely closes contacts 71'-73' in parallel with contacts 100'-102' already closed. This circuit can be traced from the source 89 through conductor 88, spring pressed contact 80' engaging contact 78' and contacts 71'-73' of the high speed differential relay to the conductor 90. Movement of the insulating member 62' of the high speed differential relay upward in Fig. 8 thus closing contacts 72'-74' has no effect upon the control circuit of differential relay 76 since these contacts are in series with open contacts 79' and 81'. A similar condition exists when the insulating member 77' of the low speed differential moves upwardly in Fig. 8. In this case contacts 101'-103' close a circuit which can be traced from one side of the source 89 through conductor 88, contacts 101'-103', conductor 93, winding 94 of differential relay 76 of Fig. 1, and conductor 97 to the other side of the source 89. Movement of insulating member 62' of the high speed differential relay, again can have no effect upon the control of the differential relay 76 as upward movement of this member merely closes contacts 72'-74' in parallel with contacts 101'-103'. Downward movement of the insulating member 62' of the high speed differential relay merely closes contacts 71'-73' which are in series with open contacts 78'-80' of the low speed differential relay. When the insulating member 77' of the low speed differential relay remains in central position, contacts 71'-73' and 72'-74' of the high speed differential relay take control as both pairs of contacts 78'-80' and 79'-81' of the low speed differential relay are closed.

The arrangement of Fig. 8 allows a somewhat smoother transition from low speed to high speed control and vice versa since one control or the other is always operating whereas in the system of Fig. 1 there may be a slight instant when no control is exercised at the time differential relay 46 is actuated one direction or the other. However, low speed differential 46 in Fig. 1 can be adjusted so that the armature always moves rapidly from its central position to an extreme position and there is no position in which the armature of any relay can remain stationary at other than central position without a control being exercised by one of the relays.

While the preferred embodiment contemplates placing the differential relays directly upon the rotor shafts of their associated power control receivers and operating certain contacts by an axially movable member extending from the shaft so as to eliminate all slip rings on the power control receiver, it is apparent that slip rings may be employed between the receivers and their differential relays so that the differential relays

may be held by stationary supporting members and all of the contacts supported by the structure of differential relays as shown by Figs. 2 to 4, inclusive. Alternatively slip rings may be employed between the contacts of the differential relays and conductors leading to the contacts so that differential relays of the types shown in Figs. 2 and 4 may be mounted upon the rotor shafts or the phase wound winding may be placed on the rotor and connected through slip rings. In any case contact pressure between the brushes and slip rings may be made as heavy as necessary to prevent dislodgment of the brushes by shock, since the rotors or power control receivers are actually turned by a prime mover which may be of any size necessary. Also either winding of any of the receivers or transmitters may be placed on either the stator or rotor and appropriate slip rings employed for external connection to the rotor.

While I have shown an electrical prime mover of the single phase condenser type induction motor, it is apparent that any type of reversible prime mover, either electrical, hydraulic or otherwise, may be employed. For installations requiring small amounts of power in the prime mover, the differential relay 76 may be eliminated and the power control contacts of the differential relays 46 and 53 employed to directly energize the prime mover while with installations requiring large amounts of power, differential relay 76 may be employed to control further relays, gas filled thermionic tubes, contactors, etc., for handling large amounts of power. Since the differential relay 76 or the differential relays 46 and 53 can be constructed to axially move a member either way from a central position, they are particularly adapted for operation of balanced hydraulic valves to control hydraulic prime mover systems conventionally employed in fire control systems. If extreme accuracy is not important, the high speed self synchronous system can be omitted and all control accomplished by the low speed system. In this case the low speed differential relay can be made to operate impulsively if desired.

The dually excited transmitters disclosed are preferred, since indicating receivers having no mechanical damping device can thereby be employed. However, conventional singly excited transmitters can be employed as far as the power control receivers are concerned and can likewise be employed with indicating receivers having friction dampers for preventing hunting or spinning. Furthermore transmitters having both A. C. and D. C. excitation, for example, those disclosed in my Patent No. 2,227,474 granted January 7, 1941, may be employed in the present system and the indicating receivers with any type of transmitters may be of any suitable type.

One of the major advantages of the present invention is that the receivers impose very little load upon the transmitters. The rotors of the power control receivers are mechanically rotated by a separate prime mover. Also the power control receivers produce voltages in the system which tend to drive the transmitter in the same direction in which they are rotated to establish an angle of disagreement. This means that the rotors of these receivers also tend to move away from rather toward zero angle of disagreement but are mechanically rotated to the zero angle by the prime mover. When the field of one of the power control receivers, for example, the field in-

5 dicated by the arrow in the transmitter 36 is out of alignment with the windings 42 and 43 unequal voltages are induced in the windings 42 and 43. If the higher voltage is induced, for example, in the winding 42, the winding 44 of the differential relay 46 is energized to a greater extent than winding 47. The armature 75 of this relay tends to move toward the core 45 thus increasing the inductance of winding 44 and decreasing the inductance of winding 47. The currents flowing through the windings 42 and 43 are thus not proportional to the voltages induced therein and the change of inductance of the circuits including the windings 42 and 43 is reflected into the phase wound windings 35 modifying the currents which flow therein. It has been found that the currents which flow in the phase wound winding 35 and therefore in the phase wound winding 13 of the transmitter 12 are such as to produce a torque in the transmitter 12 which is in a direction aiding the movement of the rotor 13 by the control member 18 as the control member 18 is actuated to produce a greater angle of disagreement between the control member 18 and the shaft 11. Since the indicating receiver 160 does constitute a load on the transmitter 12 the torque developed in the system by the power control receiver 36 at least partly compensates for the load imposed on the transmitter by the indicating receiver. The net result is that a large number of power control receivers and indicating receivers can be controlled by a relatively small transmitter. The power control receivers, however, do take current when they are at zero angle of disagreement with their transmitter and the transmitters must be large enough to supply this current to all of the power control receivers connected thereto.

40 It has been found that the total current taken by the power control receivers decreases as the angle of disagreement increases up to an angle of disagreement of 45°. This is due to the fact that the rotor winding of the power receiver which has the greatest voltage induced therein is in a circuit in which the inductance is increased 45 due to movement of the armature of the differential relay. The total current taken by a power control receiver reaches a minimum at an angle of disagreement of 45°. On the other hand the current taken by the indicating receiver is zero 50 at zero angle of disagreement and increases as the angle of disagreement increases up to an angle of disagreement of 45° reaching a maximum at said angle of 45°. Thus the change in current taken by the power control receivers 55 tends to compensate for the change in current taken by the indicating receivers so that the current delivered by the transmitter never exceeds the current taken by the power control receivers at zero angle of disagreement for any substantial 60 length of time even if indicating receivers are employed and never exceed it if no indicating receivers are employed. The current taken by the power control receivers can be made relatively low in value so that relatively small transmitters 65 can be employed without excessive heating of the transmitters.

70 While I have disclosed the preferred embodiments of my invention, it is understood that the details thereof may be varied within the scope of the following claims.

I claim:

1. In a follow-up system, a self-synchronous transmitter having relatively rotatable members with exciting windings on one member and phase-wound windings on the other member thereof,

a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of windings being connected to a winding on said device so that unbalanced voltages in said pair of windings operate said device to cause said prime mover to bring the rotor of said receiver to a position in which said voltages are balanced.

2. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device carried by the rotor of said receiver for controlling said prime mover, each of said pair of windings being connected to a winding on said device so that unbalanced voltages in said pair of windings operate said device to cause said prime mover to bring the rotor of said receiver to a position in which said voltages are balanced.

3. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device carried by the rotor of said receiver and operating a reciprocal member projecting axially from said rotor for controlling said prime mover, each of said pair of windings being connected to a winding on said device so that unbalanced voltages in said pair of windings operate said device to cause said prime mover to bring the rotor of said receiver to a position in which said voltages are balanced.

4. In a follow-up system, a low speed self-synchronous transmitter, a high speed self-synchronous transmitter, said transmitters each having relatively rotatable members with exciting windings on one member and phase-windings on the other member, the rotors of said transmitters being mechanically connected together, a low speed receiver and a high speed receiver, each having relatively rotatable members with phase-wound windings on one member, the rotors of said receivers being mechanically connected together and to a controlled member driven by a prime mover, the phase-wound windings of each of the transmitters being connected to the phase-wound windings of the corresponding receiver, a differential device for each of said receivers having means for controlling said prime mover, a pair of windings on the other member of said

receiver, each pair of windings being connected to opposed windings on the corresponding differential device so that unbalanced voltages in the pair of windings of either of said receivers operate the corresponding device to cause said prime mover to bring the rotor of said receivers to a position in which said voltages are balanced, said system having means for disabling the differential device corresponding to said high speed receiver at a predetermined angle of disagreement between said low speed receiver and said low speed transmitter.

5. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, an electric motor for driving said controlled member, a differential relay for controlling said electric motor, each winding of said pair of windings being connected to a winding on said relay so that unbalanced voltages in said pair of windings operate said relay to cause said electric motor to bring the rotor of said receiver to a position in which said voltages are balanced.

6. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of windings being connected to a winding on said device so that unbalanced voltages in said pair of windings operate said device to cause said prime mover to bring the rotor of said receiver to a position in which said voltages are balanced, and means associated with said differential device for delivering pulses of power to said prime mover tending to cause the same to rotate in opposite directions for alternate pulses, said alternate pulses being equal when said voltages are balanced and unequal when said voltages are unbalanced.

7. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of windings being connected to a winding on said device so that unbalanced voltages in said pair of windings operate said device to cause said prime mover to bring the rotor of said receiver to a position in

which said voltages are balanced, and means for alternately inserting impedances into the circuits of each of said windings of said device to cause pulses of power to be delivered to said prime mover tending to cause the same to rotate in opposite directions for alternate pulses, said alternate pulses being equal when said voltages are balanced and unequal when said voltages are unbalanced.

8. In a follow-up system, a low speed self-synchronous transmitter, a high speed self-synchronous transmitter, said transmitters each having relatively rotatable members with exciting windings on one member and phase-wound windings on the other member, the rotors of said transmitters being mechanically connected together, a low speed receiver, and a high speed receiver each having relatively rotatable members with phase-wound windings on one member, the rotors of said receivers being mechanically connected together and to a controlled member driven by a prime mover, the phase-wound windings of each of the transmitters being connected to the phase-wound windings of the corresponding receiver, a differential device for each of said receivers having means for controlling said prime mover, a pair of windings on the other member of each receiver, each pair of windings being connected to opposed windings on the corresponding differential device so that unbalanced voltages in the pair of windings of either of said receivers operate the corresponding device to cause said prime mover to bring the rotor of said receivers to a position in which said voltages are balanced, said system having means for disabling the differential device corresponding to said high speed receiver at a predetermined angle of disagreement between said low speed transmitter, said differential device for said low speed receiver being provided with an armature for controlling said prime mover and being connected to cause said armature to move substantially proportional to the unbalance of the voltages in said pair of windings of said low speed receiver, and said differential device for said high speed receiver being provided with an armature for controlling said prime mover and being connected to cause said armature to operate impulsively.

9. In a follow-up system, a low speed self-synchronous transmitter, a high speed self-synchronous transmitter, said transmitters each having relatively rotatable members with exciting windings on one member and phase-wound windings on the other member, the rotors of said transmitters being mechanically connected together, a low speed receiver, and a high speed receiver each having relatively rotatable members with phase-wound windings on one member, the rotors of said receivers being mechanically connected together and to a controlled member driven by a prime mover, the phase-wound windings of each of the transmitters being connected to the phase-wound windings of the corresponding receiver, a differential device for each of said receivers having means for controlling said prime mover, a pair of windings on the other member of each receiver, each pair of windings being connected to opposed windings on the corresponding differential device so that unbalanced voltages in the pair of windings of either of said receivers operate the corresponding device to cause said prime mover to bring the rotor of said receivers to a position in which said voltages are balanced, said system having means for disabling the differential device corresponding to said high speed receiver at

a predetermined angle of disagreement between said low speed receiver and said low speed transmitter, and said differential device for said high speed receiver being provided with an armature for controlling said prime mover and being connected to cause said armature to oscillate about a point determined by the unbalance of the voltages in said pair of windings of said high speed receiver.

10. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of windings being connected to a control winding on said device so that unbalanced voltages in said pair of windings operate said device to cause said prime mover to bring the rotor of said receiver to a position in which said voltages are balanced, said differential device including a pair of opposed cores, each supporting one of said control windings, and an armature movable between said cores, said control windings being connected to said pair of windings so that movement of said armature between said cores varies the impedance of the circuits including the windings of said pair of windings to cause said transmitter to tend to rotate away from zero angle of disagreement with said receiver.

11. In a follow-up system, a self-synchronous transmitter having relatively rotatable members with exciting windings on one member and phase-wound windings on the other member thereof, a power control receiver having relatively rotatable members, phase-wound windings on one member of said power control receiver and connected to the phase-wound windings of said transmitter, a pair of windings on the other member of said power control receiver, one of said members of said power control receiver being mechanically connected to a controlled member, a prime mover for driving said controlled member, a differential device for controlling said prime mover, each of said pair of windings being connected to a control winding on said device so that unbalanced voltages in said pair of windings operate said device to cause said prime mover to bring the rotor of said power control receiver to a position which said voltages are balanced, an indicating receiver having phase-wound windings connected to the phase-wound winding of said transmitter and power control receiver, said differential device including a pair of opposed cores each supporting one of said control windings and an armature movable between said cores, said control windings being connected to said pair of windings so that movement of said armature between said cores varies the impedance of the circuits including the windings of said pair of windings to cause said differential device to supply voltages in said system tending to drive said indicating receiver toward zero angle of disagreement with said power control receiver.

12. In a follow-up system, a self-synchronous transmitter having relatively rotatable members with exciting windings on one member and phase-

wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of control windings being connected to a winding on said device so that unbalanced voltages in said pair of windings operate said device to cause said prime mover to bring the rotor of said receiver to a position in which said voltages are unbalanced, said differential device including a pair of opposed cores supporting said control windings and providing a diamond shaped opening between the pole faces of said cores, a diamond shaped armature positioned within said opening so as to be differentially attracted by said cores, and means moved by said armature for controlling said prime mover to cause the same to rotate in one direction upon movement of said armature in one direction from a central direction, and to rotate in the opposite direction upon movement of said armature in the opposite direction from a central position.

13. In a follow-up system, a self-synchronous transmitter having relatively rotatable members with exciting windings on one member and phase-wound windings on the other member thereof, a receiver having relatively rotatable members, phase-wound windings on one member of said receiver and connected to the phase-wound windings of said transmitter, a pair of windings on the other member of said receiver, one of said members of said receiver being mechanically connected to a controlled member, a prime mover for driving said controlled member, a differential device for controlling said prime mover, each of said pair of control windings being connected to a winding on said device so that unbalanced voltages in said pair of windings operate said device to cause said prime mover to bring the rotor of said receiver to a position in which said voltages are balanced, said differential device including a pair of opposed cores supporting said control windings and having angularly disposed pole faces, an armature having pole faces corresponding to the pole faces of said cores positioned to be differentially attracted by said cores, and means moved by said armature for controlling said prime mover to cause the same to rotate in one direction upon movement of said armature in one direction from a central direction, and to rotate in the opposite direction upon movement of said armature in the opposite direction from a central position, said control winding being connected so that leakage flux from one control winding adds to the flux in the core supporting the other control winding, and contacts carried by said armature and connected in the circuit of said control windings for causing oscillation of said armature about a point determined by the unbalance in said voltages.

14. In a follow-up system, a self-synchronous transmitter, a self-synchronous receiver connected to said transmitter, and provided with a pair of windings in which unequal voltages are induced when an angle of disagreement exists between said transmitter and said receiver, a differential device having a pair of opposed cores provided with angularly disposed pole faces, a control winding on each of said cores, each of

said control windings being connected to one of said pair of windings, an armature having pole faces corresponding to the pole faces of said cores and positioned so as to be movable between said cores, a prime mover mechanically connected to the rotor of said receiver, and means carried by said armature for controlling said prime mover to cause the same to rotate said rotor into a position at which said voltages are equal.

15. In a follow-up system, a self-synchronous transmitter, a self-synchronous receiver connected to said transmitter, and provided with a pair of windings in which unequal voltages are induced when an angle of disagreement exists between said transmitter and said receiver, a differential device having a pair of opposed cores and a control winding on each of said cores, each of said control windings being connected to one of said pair of windings, said cores being shaped to provide a diamond shaped opening therebetween, a diamond shaped armature positioned in said opening so as to be movable between said cores, a prime mover mechanically connected to the rotor of said receiver, and means carried by said armature for controlling said prime mover to cause the same to rotate said rotor into a position at which said voltages are equal, and means including spring pressed contacts for returning said armature toward central position and for causing said armature to oscillate about a point determined by the unbalance of said voltages so as to deliver pulses of power to said prime mover to cause the same to tend to rotate in opposite directions for alternate pulses whereby unbalanced voltages supplied to said control windings cause alternate pulses to be unequal and said prime mover to rotate the rotor of said receiver to a position at which said voltages are balanced.

16. In a follow-up system, a self-synchronous transmitter having a rotor and a stator, a self-synchronous receiver having a rotor and a stator and being electrically connected to said transmitter, said receiver having two points of synchronism with said transmitter, a rotary control member for driving said transmitter and mechanically connected to the rotor of said transmitter or rotate at half the speed of said rotor, and a dial associated with the rotor of said receiver each half of said dial having similar graduations to indicate the angular position of said control member.

17. In a follow-up system, a rotary control member, a low speed self-synchronous transmitter having a stator and a rotor mechanically connected to said control member to have half the speed of said control member, a rotary controlled member, a low speed self-synchronous receiver having a stator and a rotor mechanically connected to said controlled member to have half the speed of said controlled member, said receiver being electrically connected to said transmitter and having two points of synchronism with said transmitter, a high speed self-synchronous transmitter, a high speed self-synchronous receiver electrically connected to said high speed transmitter and having two points of synchronism with said high speed transmitter, said high speed transmitter and receiver each having a stator and a rotor, the rotor of said low speed receiver being mechanically connected to the rotor of the high speed receiver and the rotor of said low speed transmitter being mechanically connected to the rotor of said high speed trans-

mitter to have a speed ratio of $1/n$, and means for disabling said high speed receiver for angles of disagreement between said low speed receiver and transmitter in excess of $1/2n \times 360^\circ$.

18. In a follow-up system, a self-synchronous transmitter having relatively rotatable members with exciting windings on one member and phase wound windings on the other member thereof, a receiver having relatively rotatable members, phase wound windings on one member of said receiver and connected to the phase wound windings of said transmitter for producing a field in said receiver, a control winding on the other member of said receiver, one of said members of said receiver being mechanically connected to a controlled member, a prime mover for driving said controlled member, a differential device actuated by unbalanced voltages for controlling said prime mover, said differential device being connected to said prime mover to maintain said prime mover substantially stationary when said voltages are balanced, a pair of circuits connected to said control winding in electrical quadrature and to said differential device to apply balanced voltages to said device in at least one position of said field relative to said control winding and unbalanced voltages in other positions of said field to operate said device to cause said prime mover to bring the rotor of said receiver to a position in which said voltages are balanced.

19. In a follow-up system, a self-synchronous transmitter having relatively rotatable members with exciting windings on one member and phase wound windings on the other member thereof, a receiver having relatively rotatable members, phase wound windings on one member of said receiver and connected to the phase wound windings of said transmitter for producing a field in said receiver, a control winding on the other member of said receiver, one of said members of said receiver being mechanically connected to a controlled member, a prime mover for driving said controlled member, a differential device actuated by unbalanced voltages for controlling

said prime mover, said differential device being connected to said prime mover to maintain said prime mover substantially stationary when said voltages are balanced a pair of circuits connected to said control winding at an electrical angle to each other and connected to said differential device to apply balanced voltages to said device in at least one position of said field relative to said control winding and unbalanced voltages in other positions of said field to operate said device to cause said prime mover to bring the rotor of said receiver to a position in which said voltages are balanced.

20. In a follow-up system a self-synchronous transmitter having relatively rotatable members with exciting windings on one member and phase wound windings on the other member thereof, a receiver having relatively rotatable members, phase wound windings on one member of said receiver and connected to the phase wound windings of said transmitter to produce a field in said receiver, a winding on the other member of said receiver having portions angularly disposed electrically with respect to each other whereby said field induces balanced voltages in said portions in at least one position of said field relative to said portions and an increased voltage in one of said portions and a decreased voltage in another portion at other positions of said field so that said voltages are unbalanced, one of said members of said receiver being mechanically connected to a controlled member, a prime mover for driving said controlled member, a differential device actuated by unbalanced voltages for controlling said prime mover, said differential device being connected to said prime mover to maintain said prime mover substantially stationary when said voltages are balanced said portions being connected to said differential device for applying said unbalanced voltages to said device to operate the same and cause said prime mover to bring the rotor of said receiver to a position in which said voltages are balanced.
